UNITED STATES PATENT OFFICE.

OLAF S. STROM, OF LOS ANGELES, CALIFORNIA, ASSIGNOR TO SOLAR LIGHTING FIXTURE CO., OF LOS ANGELES, CALIFORNIA, A CORPORATION.

DESIGN FOR A LIGHTING-FIXTURE BRACKET.

Application filed May 5, 1928. Serial No. 26,582. Term of patent 3½ years.

To all whom it may concern:

Be it known that I, OLAF A. STROM, a citizen of the United States, residing at Los Angeles, in the county of Los Angeles, and State of California, have invented a new, original, and ornamental Design for a Lighting-Fixture Bracket, of which the following is a specification, reference being had to the accompanying drawing, forming part thereof.

Figure 1 is a front elevation, partly in section, of a lighting fixture bracket showing my new design. It is to be noted that the candle cup at the left hand side of the figure is not completely ornamented in the same man-

ner as the cup at the right side, though it is understood that the ornamentation of this element involves a mere repetition of the ornamentation more fully disclosed.

Figure 2 is a fragmentary detail showing the bottom of the lighting fixture bracket shown in Figure 1.

Figure 3 is a fragmentary detail showing the bottom of the cup of the lighting fixture bracket shown in Figure 1.

I claim:

The ornamental design for a lighting fixture bracket as shown.

OLAF S. STROM.
